JOHN F. O'CONNOR, OF CHICAGO, ILLINOIS, ASSIGNEE TO WILLIAM H. MINER, OF CHAZY, NEW YORK.

ROLLER-BEARING.

1,357,800.

Specification of Letters Patent. Patented Nov. 2, 1920.

Application filed April 3, 1919. Serial No. 287,171.

To all whom it may concern:

Be it known that I, JOHN F. O'CONNOR, a citizen of the United States, residing at Chicago, in the county of Cook and State of Illinois, have invented a certain new and useful Improvement in Roller-Bearings, of which the following is a full, clear, concise, and exact description, reference being had to the accompanying drawings, forming a part of this specification.

This invention relates to improvements in roller bearings.

One object of the invention is to provide a roller bearing having a plurality of anti-friction rollers and adapted especially for use as a side bearing for railway cars.

A more specific object of the invention is to provide a roller bearing of the type above indicated, having improved means for returning the anti-friction rollers to their central normal position under the influence of gravity after each actuation, said means being so designed and coöoperating with the base casting that the parts will always be brought to rest when free from actuating pressure in the proper place.

In the drawings forming a part of this specification, Figure 1 is a vertical sectional view taken transversely through the ends of a body bolster and a truck bolster of a car showing my improvements in connection therewith. Fig. 2 is a top plan view of the bearing shown in Fig. 1. And Fig. 3 is a vertical sectional view taken substantially on the line 3—3 of Fig. 2.

In said drawing, 10 denotes the underside of a body bolster and 11 the upper side of an opposed truck bolster. The improved bearing is shown as applied to the truck bolster and comprises, broadly, a base casting or casing A, a pair of anti-friction rollers B—B, and a pair of weights C—C.

The casting or casing A is of substantially rectangular formation and has parallel side walls 12—12, end walls 13—13, lower horizontal wall 14 and perforated corner lugs 15 by which it is riveted or bolted to the bolster. The lower wall of the casing or retaining member A is adapted to take the load from the rollers and is preferably provided with a steel insert indicated at 115 to provide better wearing qualities. The bottom wall is suitably recessed as at 16 to accommodate the insert 115 so that the upper face of the latter lies flush with the

top surface of the remaining portion of the bottom wall. To hold the steel insert in position I provide a pair of overhanging lugs 17—17 at one end under which the insert 115 is inserted and at the other end of the plate a cotter 18 is extended through the wall 13 in such manner as to overlap the insert 115 and hold it against accidental removal. The casting may be cut away in the end walls as indicated at 19—19 in order to permit dirt and other foreign matter to be cleared therefrom.

The two rollers B are each of cylindrical form and of similar diameter and each is provided at its ends with pairs of laterally extended pins 20—20. Said pins 20, when both rollers are in normal position will stand in the same horizontal plane as will be evident from an inspection of Figs. 1 and 2.

The weights C are counterparts and a description of one will suffice. Each weight C is preferably in the form of a plate having four downwardly opening curved slots 21—21. The slots 21 are arranged in pairs of opposite curvature and so disposed that the pins 20 of the rollers will all seat simultaneously against the plate at the top of the openings 21, as clearly appears from an inspection of Fig. 1. The weights C all bear on the pins 20 and hold the pins 20 in their lowermost position with the rollers B uniformly spaced. As the rollers B are rolled to either side of normal it is evident that one pin at each end of each roller B will rise so that the plates or weights C will be lifted and always maintained in a horizontal position.

Such a condition of the parts is illustrated by the dotted lines of Fig. 1 where the rollers are shown in their extreme position to the left, the left-hand roller B having come into contact with the left-hand end wall 13. If now the actuating pressure is removed from the rollers B, it is evident that the weights C all bear on the elevated pins 20 so as to roll the rollers B back to the original position.

In order to insure the return of the rollers B to their central position after each actuation of the bearing and also to prevent possibility of the rollers being shifted lengthwise of the base casting due to jarring or vibration, I provide the following means. On each side of the base casting A and at each end thereof, in alignment with the corresponding weights C, I provide an inclined

shoulder as indicated at 22—22. The adjacent ends of the weights C are correspondingly beveled or inclined as indicated at 23 and the length of the weights C is such that 5 there is a slight clearance normally between the beveled ends 23 and the inclined shoulders 22 of the base casting. The bevel of the ends 23 and incline of the shoulders 22 is made such that there will be no interference with the elevation of the weights C as 10 the rollers move to either side of normal, assuming that the parts start from the position shown in the drawings. Any tendency of the rollers and weights C to be shifted 15 longitudinally will be limited by engagement of the weights with the inclined shoulders 22 and similarly, after the weights C have been elevated as the weights fall during the rotation of the rollers B the weights 20 will be positively centered by the inclined shoulders 22.

Although I have herein shown and described what I now consider the preferred manner of carrying out the invention, the 25 same is merely illustrative and I contemplate all changes and modifications that come within the scope of the claims appended hereto.

I claim:

- 30 1. In an anti-friction bearing, the combination with a hollow retaining member, of a plurality of anti-friction rollers disposed within said member, a weight within said member, and duplicate sets of projections 35 on said rollers engaging said weight, one set being adapted to elevate the weight when the rollers are moved in one direction and the other set to elevate the said weight when the rollers are moved in the opposite direction.
- 40 2. In an anti-friction bearing, the combination with a hollow retaining member, of a plurality of anti-friction rollers disposed within said member, each of said rollers having a pair of spaced projections, and a slotted gravity actuated plate mounted on said projections and adapted to be elevated when the rollers are moved to either side of normal, the plate being adapted to return the rollers to normal position upon removal of the actuating pressure.
- 45 3. In an anti-friction bearing, the combination with a hollow retaining member having side and end walls, of a plurality of

anti-friction rollers mounted within said 55 member, each of said rollers having a pair of projections extending from each end thereof, a gravity actuated plate at each end of the rollers and slotted to fit over said projections, and means on the base casting 60 co-operable with said plates to position the latter with respect to the base casting and prevent abnormal shifting of the rollers with respect to the retaining member.

4. In an anti-friction bearing of the character described, the combination with a hollow substantially rectangular retaining member having a horizontally extending bearing surface therein; of a plurality of anti-friction rollers within said retaining 70 member and adapted to roll back and forth on said bearing surface; a gravity controlled plate independent of the retaining member and disposed therein; and co-operating means on said plate and each of said rollers 75 so arranged that, upon rolling movement of the rollers to either side of normal position, said plate will be elevated and automatically return said rollers to normal position upon removal of the actuating pressure, said plate 80 and retaining member having co-operating means for centering said plate with respect to the retaining member.

5. In an anti-friction bearing of the character described, the combination with a hollow substantially rectangular retaining member adapted to be secured to a truck bolster and provided on its interior with a flat bearing surface and inclined ledges at each end thereof and on opposite sides; of a 85 plurality of anti-friction rollers disposed within said retaining member and adapted to roll back and forth on said bearing surface; gravity actuated plates disposed at the opposite ends of said rollers and in 90 alinement with said inclined ledges; and co-operating means on said rollers and plates arranged to elevate the latter as the rollers move to either side of normal position, said rollers extending above the top of the 95 retaining member and adapted to co-operate with an opposed bearing surface.

In witness that I claim the foregoing I have hereunto subscribed my name this 22nd day of Feb., 1919.

JOHN F. O'CONNOR.

Witness:

CARRIE GAILING.
